UNITED STATES PATENT OFFICE

ALVIN G. SHERMAN, OF GROSSE POINTE, MICHIGAN, ASSIGNOR TO DETROIT VAPOR STOVE COMPANY, OF DETROIT, MICHIGAN, A CORPORATION OF MICHIGAN

DESIGN FOR A HANDLE FOR STOVE DOORS AND THE LIKE

Application filed November 7, 1929. Serial No. 33,363. Term of patent 7 years.

To all whom it may concern:

Be it known that I, ALVIN G. SHERMAN, a citizen of the United States, residing at 216 Lakeland Avenue, Grosse Pointe, in the county of Wayne and State of Michigan, have invented a new, original, and ornamental Design for a Handle for Stove Doors and the like, of which the following is a specification, reference being made to the accompanying drawings, forming part thereof.

Fig. 1 is a front elevation of the handle showing my new design.

Fig. 2 is a plan view of the handle.

I claim:

The ornamental design for a handle for stove doors and the like, substantially as shown.

ALVIN G. SHERMAN.
